(57) **CLAIM**

The ornamental design for an upper liner, as shown and described.

DESCRIPTION

FIG. 1 is a top perspective view of an upper liner showing my new design;

FIG. 2 is a bottom perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a side elevational view thereof, the opposite side being a mirror image; and,

FIG. 8 is a cross-sectional view thereof, taken along line 8-8 in FIG. 3.

The broken line portions illustrate environmental structure and form no part of the claimed design.
